ROSE PLATE

George P. Patriquin, Gardner, Mass., assignor to Ilco Corporation, Fitchburg, Mass., a corporation of Massachusetts

Filed July 30, 1968, Ser. No. 12,966

Term of patent 14 years

Int. Cl. D8—03

U.S. Cl. D8—179

FIGURE 1 is a perspective view of the rose plate in accordance with my invention;

FIGURE 2 is a side elevational view thereof;

FIGURE 3 is a rear elevation thereof;

FIGURE 4 is a partial enlarged section along the line 4—4 of FIGURE 1.

I claim:

The ornamental design for a rose plate, substantially as shown.
